UNITED STATES PATENT OFFICE.

ROBERT T. HAZELTON, OF CINCINNATI, OHIO, ASSIGNOR TO THE CINCINNATI SHAPER COMPANY, OF CINCINNATI, OHIO, A CORPORATION OF OHIO.

LUBRICATING DEVICE.

Application filed August 22, 1924. Serial No. 733,656.

This invention relates generally to improvements in lubricating systems and is particularly adapted to deliver oil in proper quantity to various parts of a machine or 5 like device, only while the machine is in operation.

The invention has been shown applied for the lubricating of a metal shaper of the reciprocating ram type, for which machine the 10 invention is particularly adapted, the embodiment shown having been specially designed for such a machine. It will be readily apparent, however, that the general principles of the invention may be applied to 15 various types of machine tools.

One object of the invention is to provide a system wherein an auxiliary central distributing reservoir of small capacity is arranged to deliver oil in relatively small 20 quantities, as by drops, to the parts to be lubricated, only while the machine is in operation, the capacity of the reservoir being for this purpose limited so that when the lubricant supply thereto is cut off or interrupted 25 the reservoir drains into a return pipe and immediately ceases to function as a distributor, thus preventing waste by leakage when the machine is idle.

I have found that with the ordinary type 30 of force feed lubrication or sight feed lubrication either too much oil is delivered to certain parts, or the system becomes clogged and the proper amount of oil is not delivered. For that reason in the present design the 35 lubricant is delivered by gravity to all parts to be lubricated, this delivery by gravity being regulated by wicks adapted to siphon lubricant from a small relay reservoir, above the parts, which is supplied by a pump 40 placed in a main reservoir at a lower elevation. The small relay reservoir receives the pumped oil or lubricant and the lubricant is maintained at a level within this reservoir below that of the discharge openings leading 45 therefrom, in which the wicks are placed, and at a level above an overflow passage which leads the oil back to the main distributing reservoir. The relay reservoir is further provided with an opening leading 50 from its bottom downwardly and into this overflow passage whereby when the oil supply to the relay reservoir is cut off the residual oil in the reservoir is completely drained off into a return pipe or conduit.

Thus provision is made for substantially immediately cutting off the supply of oil to the parts to be lubricated as soon as the machine ceases to operate, the pump in this instance being operated from a shaft forming part of this transmission and speed 55 change mechanism.

Another object of the invention is the provision of means for delivering oil to reciprocating parts from a stationary reservoir mounted independently of said parts 60 and particularly to provide a device of this nature adapted to deliver oil through the ram of a metal shaper, through the link connecting the ram with the pitman and to the pitman slide and pivots. 70

Another object of the invention is to provide a sight feed drip lubricating system of the above nature adapted to deliver lubricant into distributing tubes in a quantity exactly proportional to the needs of the 75 parts to be lubricated and to further provide a compact distributing reservoir of small capacity arranged for delivering variable quantities of lubricant according to the need.

Other objects and certain advantages will 80 be more fully set forth in the description of the accompanying drawings forming a part of this specification in which:

Figure 1 is an end view of a shaper, parts being broken away to particularly show the 85 path of the overflow or return lubricant from the auxiliary to the main distributing reservoir.

Figure 2 is a side elevation partly in section, illustrating the crank gear, pitman and 90 pitman connection to the ram, as well as the main distributing reservoir and pump therein.

Figure 3 is a detail longitudinal section showing the telescopically arranged lubricant delivery conduit for supplying lubricant to the nut and link of the ram. 95

Figure 4 is a cross section on line 4-4, Fig. 3, illustrating the relation of the nut and showing the passages through the clamp 100 block.

Figure 5 is an enlarged longitudinal section of the telescoping members.

Figure 6 is a side elevation of the pump, partly in section. 105

Figure 7 is a detail sectional elevation taken on line 7-7 of Fig. 6.

Figure 8 is a plan section taken through

the glass annulus or window of the auxiliary relay reservoir.

Figure 9 is a similar view through the upper compartment thereof.

5 Figure 10 is a vertical section approximately on line 10—10 of Fig. 9.

Figure 11 is a vertical section approximately on line 11—11 of Fig. 8.

10 Figure 12 is a vertical section approximately on line 12—12 of Fig. 8.

Figure 13 is an enlarged detail section through one of the siphon delivery passages showing the wick siphon in place and illustrating its mode of attachment.

15 For purposes of simplification only those portions of the shaper are illustrated which are to be lubricated or which function to receive, convey, circulate or store the lubricant.

20 The main frame 1 is mounted upon a suitable base and has the usual dove-tail guide-ways or rails 2 for longitudinally slidably supporting the reciprocable ram 3. Both the frame and ram are of hollow construction, various reinforcing flanges and partition walls being provided respectively to give rigidity to the frame and provide compartments for housing various parts of the mechanism.

30 The frame at the rear end and lower part is partitioned to provide a gear housing compartment 5 adapted for completely and separately housing the transmission and speed change gearing which drives the crank gear, 35 and this compartment acts as a main distributing and receiving reservoir from which, as the lowest point of the system, the oil is pumped to the highest point, and to which an overflow unused portion of the

40 same returns. Only the main driving shaft 6 is shown, the omission of the other elements of the gearing being deemed advisable to avoid unnecessary detail, particularly in view of the fact that the gearing is fully 45 illustrated and described in applicant's co-pending application for improvements in shapers filed July 21, 1922.

Keyed to the shaft 6 is a gear 7, in this case a worm gear, which meshes with a corresponding gear of a pump mounted within the reservoir, which pump will be fully described.

50 The crank gear 10 has a lateral, hollow, cylindrical extension 11 rotatably journaled in a horizontally disposed bearing sleeve 12 removably non-rotatably held in an opening provided in the side wall of the frame, this bearing being extended beyond the end of the cylindrical extension to form a housing 55 13 acting both as an intermediate catch and overflow basin for the lubricating system, and for enclosing portions of the carriage feed transmission mechanism, certain elements of which are lubricated from above 60 and certain other elements, generally indi-

cated at 14, in the lower part of the casing, dipping into and being partially submerged in the lubricant at the bottom of the casing 13, from which lower point the oil overflows into the pump reservoir 5, in a manner to be 70 fully described.

The ram is reciprocable by a pitman 15 which is pivoted at its lower end to the frame as at 16, the lower end being provided with a hub through which the pivot passes 75 and the pivot having its opposite end engaged in bearings in the opposite side walls of the frame. The pitman has the form of a frame-like casting suitably ribbed to give rigidity, having its upper end bifurcated 80 as at 17 to receive and pivot one end of a link 18 secured by the pivot 19, the opposite end of the link being pivotally connected as at 20 to a nut or shackle block 21 adjustably engaged with horizontal longitudinal guides 22 within the ram, said nut being traversed and in threaded engagement with a screw 23 which when rotated causes adjustment of the nut relative to and lengthwise of the ram. The nut is provided with an upwardly extending terminally threaded rod 25 which extends through a longitudinal slot 26 at the upper side of the ram, and through a clamp block 30 which acts as a lubricant conveyor having intersecting passages 90 therethrough for conveying lubricant to parts therebelow, in a manner more fully described. In threaded engagement with the upper end of the rod is a clamp nut 31 which engages the clamping block 30 and is adapted to clamp the nut 21 and block 30 against movement after adjustment. The nut provides means for adjustably connecting the ram and pitman, and for changing their relation to obtain varying degrees of 100 overhang at the forward end of the ram with respect to the work table.

The quantity and rate of flow of lubricant to the parts to be lubricated is obtained and controlled by means of an auxiliary or relay reservoir placed at the highest point of the system, into which the lubricant is forced by means of a pump disposed in a main reservoir preferably at the lowest point of the system. The relay reservoir is of relatively 110 small cubical capacity and is adapted to deliver quantities of oil to each part to be lubricated, proportional to the need, the arrangement being such that when the oil supply to the reservoir is cut off the surplus oil in the reservoir is returned to the supply or main reservoir.

115 The auxiliary reservoir is mounted adjacent the ram and upon the upper side of the main frame at the rear thereof and substantially vertical above the reservoir 5, and has the form of a tower-like casing 40, preferably of cast construction having a horizontal partition 41 adjacent its upper end dividing it into upper and lower compart- 120 125 130

ments, the upper of which has a small cubical capacity. A diametrically disposed elongated depression 42 is formed in the upper side of the partition and a vertically disposed integral extension 43 rises from the bottom of this depression to a point level with the horizontal top of the casing. The extension is bored axially to provide a vertical passage or duct 44 traversing extension 5 and partition. A series of vertical concentrically spaced passages 45 are formed in and through the partition laterally of the depression, by boring and counterboring, thus providing passages opening above the bottom of the depression and slightly below the top of the casing, the upper enlarged portions of the passages providing pockets for catching drippings of lubricant from passages in a small reservoir thereabove, in a manner to be described. In addition to the counterbored passages just mentioned, the partition is further bored vertically also laterally of the longitudinal depression and concentrically with the casing axis to provide catch depressions 46, one of which is adapted to overflow into the other through a connecting channel 47, this for the purpose of doubling the oil supply to the nut, link and pitman. Through an exterior horizontally disposed boss of the casing extends a bore 48 intersecting one of the depressions, this bore being enlarged at its outer end by counterboring and threaded for engagement by a coupling gland 49 connected with which is a pipe 50, extending horizontally rearwardly of the frame parallel with the ram slideway, and bent upon itself to provide a parallel leg 51 extending in the opposite direction and adapted to enter telescopically within a companion larger tubular chamber section, mounted non-movably within the bore at the extremity of the block 30 attached to the ram and parallel to the ram. The upper side of this casing is machined to provide a seat 52 upon which is placed a gasket and upon the gasket is seated a glass cylinder 53 providing a circumferential sight opening through which the operation of the system can be observed at this point. Mounted upon this glass annulus is a relatively small cylindrical reservoir 55, closed at the top by a removable cover 54, circularly grooved upon its bottom for sealing engagement with the glass ring and having a diametrically disposed depression 56 in the upper side of its bottom wall and a boss 57 rising at one side within the depression and also projecting below the bottom as at 58, for sealing engagement with the corresponding extension 43 of the lower casing, which extension, as before mentioned, rises from the diametric depression therewithin. This extension of the upper reservoir has two bores, 59, 60 therethrough, one, 59, registering with the corresponding bore 44 of the lower extension just mentioned to form a reservoir intake connecting directly with the force pump through the tube, and the other, 60, aligning with the opening 61 connected by the pipe 64 with the opening 62 in the frame above the crank journal. The two bores 59, 60 communicate with the interior of the reservoir at relatively different levels but both at lower levels than a series of vertically disposed concentrically arranged passages 65, 66, corresponding to those in the lower casing, in alignment therewith and adapted to discharge thereinto. There are in this instance six of these passages counterbored in a manner similar to those of the lower casing. The upper casing is removably attached by screws 67.

In this design seven overflow passages are provided, four of which are in communication with slide faces of the ram guides, two adapted to supply the pitman, pivots and connections between the same and the ram, and one, a return or overflow, connected with the casing surrounding portions of the cross-feed mechanism adjacent and laterally of the crank gear including the crank gear bearing. The casing acts as an intermediately disposed overflow reservoir leading through an intermediate compartment to the main distributing reservoir.

The auxiliary relay reservoir is purposely made of small capacity and is adapted to regulate the distribution of lubricant through separate channels, the number of channels substantially corresponding to the number of stations or parts to which the lubricant is to be delivered. Thus, the lubricant is delivered to the uppermost reservoir in which its level is maintained at a point between the overflow 60, and delivery passages 65, 66.

In order to provide a drop feed through the passages 65, 66, wicks 71 are placed as shown in Figures 11 and 13 in each distributing passage of the top reservoir and act to siphon the lubricant after the pump ceases to operate.

Inasmuch as the passages are connected with those parts of the machine to which the lubricant is to be delivered in relatively smaller quantity than to other parts, the wicks act to deliver lubricant into the passages drop by drop only, and the level of the oil in the reservoir is not allowed to reach the level of the intake ends of the passages. Whenever the oil supply in the chamber 55 is interrupted, the chamber is quickly drained through the orifices 60, 57^a whereby delivery of oil is also interrupted through the siphon-like wicks. While oil is being supplied to the reservoir the level of oil is maintained at some point between the intake end of the overflow opening 60 and the level of the intake ends of the bores 65, 66.

In order that the wicks may properly

130

function as capillary siphons each must be retained in position with its delivery end below the level of the intake end and for this purpose each wick is knotted as shown at 6 71^a, a wire 71^b being engaged in the knot, extended through the passage, and crimped on the lower side. (See Fig. 13.) The knot is of less diameter than the counter-bored portion of the passage and said 10 knot is held against the bottom of the passage as shown. In order to prevent clogging at the lowest end of the wick, small counter-bores forming cavities 66^a are made within the bottom wall of the larger bore, these 15 bores being axially related as shown in Fig. 9.

The intake end of the overflow or return conduit within the relay reservoir is at a lower level than the intake ends of the opening or openings of the gravity supply conduits but above the level of the intake passage to the reservoir and the oil level is normally kept at a point between these levels. Thus the oil is delivered only to the 25 upper levels through the siphon wicks, one wick being provided, as before stated, for each conduit.

An important feature of the invention is the manner of oiling the link and rocker 30 arm, by means of a telescopic conduit connecting a stationary reservoir mounted upon the frame, with a member carried by the ram, whereby the lubricant connection is maintained at all times. For this purpose 35 the block 30 is longitudinally bored as at 35, (see Fig. 4), and has an upturned enlarged extension at its outer end which has a relatively larger cross-bore 36 therein, enlarged intermediate its ends as at 37 to form an 40 annular chamber or passage. These passages are communicating, the bore 35 being tangent to the bore 37 at the lower side thereof, so that lubricant may be delivered by gravity from the cross-chamber to the longitudinal passage. Moreover, the longitudinal passage is disposed at one side of the block and connects with the chamber at that 45 end nearest the tool end of the ram permitting the rod 25 to pass through the block 30 at one side of the channel 35. A short passage 75 intersects the passage 35 at a point 50 vertically over the nut 21, and a tube 76 connects this short passage with a vertical passage 77 of the nut. The nut is provided 55 with a bore 78 of larger diameter than the screw 23 through which the screw extends and this bore is intersected by the vertical passage 77 as shown in Figs. 3 and 4, which extends vertically through the nut from top 60 to bottom portions of the passage lying at opposite sides of the screw. A circumferentially grooved collar 79 is disposed loosely about the screw shaft and is held immovably within the bore in registration with the two

bores of the passage, whereby oil is permitted to pass around the shaft through the bottom opening and into a groove 80 formed longitudinally in the upper side of the link 18.

The specially designed link, (see Figs. 2 70 and 3), is additionally provided with a cross-channel 81 leading from the groove 80 at a lower level, from which cross-channel extends a longitudinal passage 81^a tangent to and partially intersecting the periphery of 75 the cross pin 20, for oiling the same, suitable absorbent packing or wick being placed within the opening to prevent leakage. At the opposite end of the groove or channel of the link is a vertical bore 82 leading to the 80 bore through which the pin 19 passes, through which the oil reaches the pin and overflows laterally therefrom into a cavity 83 formed centrally at the bottom of the bifurcation of the pitman. A bore 84 leads from 85 this cavity downwardly and opens into an elongated slot or opening extending longitudinally of the pitman, the sides of which form guides for the crank pin block 85. This block has a cavity 86 in its upper face 90 and passages 87 leading laterally from the cavity to the slide faces as well as a passage 88 leading downwardly therefrom tangent to and partially intersecting the crank pin 89. This passage may be filled with a wood wick 95 to prevent any undue supply of lubricant to the crank pin. The cross-bore of the block through which the crank pin extends is grooved longitudinally as at 90, in its upper side to provide lateral outlet for the 100 oil or lubricant which, after escape therefrom, flows down the slide faces into a cavity 91 at the lower end of the guide slot through which cavity extends vertically 105 downwardly a passage 92 leading to the pivot 16.

In order to deliver the lubricant from the lower compartment of the oil tower to the passage 37 of the block 30 while the ram is reciprocating, the open end leg 51 of the 110 bent tube 50 is telescopically engaged within a closed end tube of substantially larger diameter adjustably mounted within and movable with the block in the following manner:

The larger tube 95 as a closed chamber is 115 engaged through an opening 36 at the end of the block 30 (see Fig. 5), and secured by set screws 96. The tube extends beyond the block toward the forward end of the machine, and has an opening 97 adjacent its 120 rear end lying within and communicating with the chamber 37. The outer forward end of the tube is closed by a plug 98. The relative diameters of the tubes are such that a circumferential channel is formed therebetween and the open end inner tube 51 slides in a fiber or wooden bushing 99 held 125 in place by steel washers on both sides of

the bushing. The tube 51 is free to move in this bushing. The bushing dams the oil in the larger tube 95.

By means of this telescopic arrangement, 5 a proper amount of oil to the nut, link and pitman is assured at all times and a relatively larger amount of oil is obtained through the ducts 66, 46, for this purpose.

The frame is bored diagonally at 63 and 10 the tube 64 connects therewith. Vertically below the discharge end of this opening the bearing sleeve is longitudinally grooved or channelled as at 100 and has a bore 101 leading therefrom and opening against the outer 15 surface of the tubular crank gear shaft 11. A passage 102 leads forwardly from the outer end of the chamber and opens into the casing 13, a tube 103 being inserted therein to carry lubricant to a point above the mechanism in the casing. Adjacent the outer end 20 of the channel 100 and leading from the longitudinal passage 102 is a vertical passage 104 extending through the bushing or sleeve 12 adapted to deliver oil at a midpoint of 25 the crank gear journal 11, and the outer portion of the bore of the sleeve is longitudinally grooved at the top as at 105 to provide a path for lubricant leading to the forward end of the journal. The casing 13 adjacent 30 the bottom is bored horizontally as at 106 and the frame correspondingly bored as at 107 in alignment with the first mentioned bore to provide a continuous passage from the casing to the compartment 70, formed 35 within the rear end of the frame adjacent the main reservoir 5, with which chamber 70 communicates through an elongated opening 109 shown in Figs. 1 and 2.

The crank gear bushing is further provided at its inner end face with a depression 40 110 the circumferential wall of which is undercut as at 111 to provide a lubricant catch channel from the lowermost point of which a cross bore 112 leads downwardly towards 45 and opens into the chamber 70. A vertical bore 113 leads upwardly from the lower part of the casing 13 through which lubricant may flow through openings in the casing 113 and main frame immediately below the 50 crank gear bushing 12.

Bores 115 lead downwardly from the work faces of the ram guides at each of the four corners, and bores leading from one of the guide faces are respectively intersected by 55 bores 116 extending downwardly and inwardly from the top of the frame, these latter bores being closed at the top by a screw threaded plug and being connected at their bottoms by pipes 120 with respective 60 passages 45 of the relay reservoir. One bore leading from the work face at one end of one guide intersects a vertical bore 117 leading downwardly from the top face of the frame which bore is connected by the tube 120 with

one of the passages 45 of the relay reservoir. 65 The tubes leading to the various stations and parts pass from the interior of the frame through an aperture 125. The faces of the slides are further grooved diagonally as shown at 121, in Fig. 2, at each side of and 70 communicating with the bores, thus providing passages whereby lubricant may be forced to the faces of the slides.

A gib 130 is interposed between the ram and guide and is bored cross-wise as at 131 75 in Fig. 12, and the gib face is grooved as at 132 and the groove in said face registers both with the transverse groove and with the corresponding lubricant receiving passage whereby lubricant is delivered to slide 80 and gib faces.

The reservoir for delivering lubricant to the nut, link and pitman may be of more simple structure if it is desired to deliver oil by gravity in the ordinary manner and 85 where it is not desired to interrupt the oil flow as soon as the machine is stopped. In such a case the telescopic arrangement is used substantially in the same manner except that the pipe 50 is connected at the bottom of a reservoir preferably of greater capacity than the small relay reservoir. 90

In this system of complete lubrication, however, the smaller relay reservoir is provided in order to cut off the oil supply to the 95 parts as soon as the machine stops and for this purpose a force pump is used and, as before stated, is mounted in the reservoir 5 and operated through the gear 7 mounted on the shaft 6 as one of the elements of transmission and speed change gearing for transmitting the crank gear. 100

The pump is disposed at the lowest part of the lubricating system, and is herein attached to and completely housed within the 105 main frame, and separately within the compartment 5 provided within the frame for the transmission and speed change mechanism for driving the crank gear.

This compartment, as before mentioned, 110 is formed by sub-dividing the rear end of the frame by partitions which are integral with the walls of the frame. The speed and transmission gear is not herein shown because it forms subject matter of applicant's 115 co-pending application for improvements in shapers filed July 21, 1922.

The pump, however, is adapted to be driven whenever the shaper is in operation through one of the gearing driving shafts 120 6 mounted within the compartment, to which shaft is keyed a driving worm wheel 7. The compartment 5 forms a main lubricant receiving and distributing reservoir into which surplus oil, drained from certain parts of the machine, is received and from which the oil is pumped to other parts of the machine, the used oil being replaced by refilling. The 125

- oil within the casing normally lies at such level as to assure lubrication of various parts therewithin, and the gears, not shown, dip into or run in the lubricant.
- 5 The pump is of the reciprocating plunger type and has the form of a casting having a body portion 140 adapted for vertical disposal during operation, providing a central plunger receiving bore 141 of relatively 10 large diameter, and two bores 144, 145, each of less diameter are disposed laterally of the larger bore. Each bore is connected at its inner end with the plunger bore respectively by cross-passages 142, 143, one of 15 which, 142, the inlet, intersects an axial counter bore 146 of the plunger bore, a conical seat 147 being formed at the intersection of the bores against which is seated a gravity actuated ball valve 148 of less diameter than 20 the plunger bore adapted to close the intake passage when the pump is discharging. The cross-passages are disposed at right angles to the axes of the intake and discharge passages and intersect respective passages as well as 25 the plunger bore. Each cross-passage is closed at its outer end by a suitable thread plug. The inlet end of the intake passage is disposed at the upper side of the pump and when the pump is operatively attached with 30 in the reservoir it is adapted to lie just beneath the surface of the lubricating bore to prevent entrance of sediment.
- The intake and discharge passages are parallel with the plunger bore in one plane 35 but inclined thereto in another plane the upper end of the discharge passage lying at one side of the shaft 6, in a readily accessible position from a point outside the shaper frame.
- 40 The pump casing is bored concentric with the discharge passage to provide a valve chamber 150 within which is a gravity actuated ball valve 151 of less diameter than the counterbore, adapted to fit a conical seat 45 152 at the intersection of the bores to prevent back flow during the intake stroke of the pump. The end of the pipe line 153 leading to the relay distributing reservoir at the top of the machine has threaded connection with the discharge passage of the 50 pump, as at 154.
- A stub shaft 155 is rotatably, horizontally supported at one end in a bearing 156 upon the top of the pump casing, and has keyed 55 upon its projecting end a gear 157 meshed with the companion gear 7 upon the drive shaft 6. Beyond and adjacent the gear is keyed a cam 158 having the form of an eccentric sleeve overlying and engaging the 60 upper end of the plunger 159 reciprocable in the bore 141. The plunger at its upper end has a circumferential flange 160 forming a shoulder between which and the top of the pump body is interposed a coiled expansion spring 161 adapted to urge the

plunger outwardly against the cam, which cam when rotated obtains a discharge stroke of the plunger against the action of the retraction spring. Upon the discharge stroke of the plunger the ball valve 148 closes and the valve 151 opens, the valve action being reversed upon the intake stroke.

Integral with and extending laterally from the pump body is an attachment arm 165 adapted to be fastened to the vertically 75 disposed lug 166 adjacent the assembly opening 167 of the frame, which opening is closed by a suitable outwardly dished cover 168.

The pump when attached has its passages substantially vertically disposed, the parts being readily accessible for repair or adjustment from the outside of the frame. Moreover, the pump is adapted for operation by one of the main drive shafts of the machine 85 which shaft is in operation whenever the machine is in operation, thus insuring the operation of the pump for supplying lubricant exactly and only when needed.

Having described my invention, I claim:

1. In a lubricating system, the combination with a machine having bearings, of an oil reservoir at a low elevation, an oil distributing reservoir at an elevation above the bearings, a pump for elevating oil from the said low elevation reservoir to the distributing reservoir, an overflow duct communicating with the distributing reservoir for maintaining a normal oil level in said distributing reservoir during the operation of the pump, and draining the same when the pump operation ceases, said overflow duct directing the oil for return to said low elevation reservoir, oil distributing ducts communicating with said distributing reservoir at an elevation above the overflow duct, and leading to respective bearings, and a siphon wick respectively for each of said distributing ducts, engaged into the duct and distributing reservoir for supplying a slow or drip feed to said distributing ducts.

2. In a lubricating system, the combination with a machine having bearings, and a plurality of transmission housing and oil holder compartments having oil drainage connection, one compartment thereof at a low elevation, providing a reservoir, an oil distributing reservoir at an elevation above the bearings and compartments, a pump for elevating oil from reservoir of said low elevation compartment to the distributing reservoir, an overflow duct communicating with the distributing reservoir for maintaining a normal oil level in said distributing reservoir during the operation of the pump, and draining the same when the pump operation ceases, said overflow duct directing the oil for return through the transmission compartments to said compartment reservoir, oil distributing ducts communicating 115 120 125 130

with said distributing reservoir at an elevation above the overflow duct and leading to respective bearings, and a siphon wick respectively, for each of said distributing ducts, engaged into the duct and distributing reservoir for supplying a slow or drip feed to said distributing ducts.

3. In a lubricating system, the combination with a machine having bearings, of an oil reservoir at a low elevation, an oil distributing reservoir at an elevation above the bearings, a pump for elevating oil from the said low elevation reservoir to the distributing reservoir, lubricant distributing ducts communicating with said distributing reservoir, and a siphon wick respectively for each of said distributing ducts, engaged into the duct and distributing reservoirs for supplying a slow or drip feed to said distributing ducts, the continuity of said distributing ducts broken beneath the base of said distributing reservoir to provide a sight chamber.

4. In a lubricating system, the combination with a machine having bearings of an oil reservoir at a low elevation, an oil distributing reservoir at an elevation above the bearings having an overflow providing a return drain to said low elevation reservoir, and ducts for leading oil by gravity to the respective bearings, siphon wicks in said ducts and reservoir for supplying a slow or drip feed to said ducts, a support for said distributing reservoir, providing a head for mounting oil distributing conduits in a spaced relation and respective alignment with said ducts and forming a sight space therebetween, transparent means interposed between said reservoir and support head and forming a sight chamber.

5. A lubricating system comprising an upper distributing reservoir of small capacity having outlets at different levels, an inlet at a lower level, said outlets adapted to deliver by gravity through the bottom of the reservoir, a relatively smaller passage leading from the bottom of the reservoir into one of the outlets, a supply reservoir below said distributing reservoir, and means for forcing liquid upwardly to said distributing reservoir.

6. A lubricating device comprising superposed reservoirs, the upper having a passage for delivering fluid thereto at a level above its bottom, vertically aligned delivery passages in said upper and lower reservoirs, the upper adapted to drop fluid into the lower when the upper reservoir overflows through its passages, and siphon-like wicks having their legs extending respectively into said upper reservoir and into certain of the delivery passages therein, for drawing relatively small amounts of lubricant from the upper reservoir into those passages.

65 7. A lubricating device comprising su-

perposed closed reservoirs, a glass annulus interposed between said reservoirs and sealingly engaged therewith to provide a circumferential window, a passage for delivering fluid into said upper reservoir, delivery passages in said upper and lower reservoirs vertically aligned, the passages in the upper reservoir opening therewith at different levels and adapted to deliver fluid into the lower, and wicks extending into those passages at highest level for siphoning small quantities of lubricant from the upper reservoir into certain of the passages, and a drain opening leading from the bottom of the reservoir and intersecting one of the non-wick containing overflow passages.

8. In a device of the class described, a frame, a ram thereon, a pitman pivoted at the lower end of said frame, a link pivoted at opposite ends respectively to the upper end of said frame and ram, said ram, pitman and link having passages therethrough for conveying lubricant from the ram to the pitman and link, a chamber in said ram in communication with the ram passage, a reservoir upon the frame and a tube leading from the reservoir to said chamber having a sealing telescopic engagement therewith and in communication through said chamber with said passages.

9. In a device of the class described, a frame, a ram reciprocable thereon, a pitman pivoted to said frame, a link connecting the upper end of the pitman with the ram, said ram, link and pitman having communicating oil passages therethrough for conveying lubricant to the parts to be lubricated, a chamber upon said ram parallel therewith communicating with the ram passage, a reservoir upon the frame and a tube leading from the reservoir to said chamber engaged telescopically therewith and adapted to deliver lubricant through said chamber and into said passages.

10. In a device of the class described, a frame, a ram reciprocable thereon, a pitman pivoted at its lower end to the frame, a link pivoted at one end to the upper end of the pitman and at its opposite end to the ram, said link having a groove in its upper side and passages leading therefrom to the pivots of the link, a passage in said ram leading to the groove, a chamber in said ram communicating with said passage, a reservoir upon the frame and a tube leading from the reservoir having sealing telescopic engagement with the chamber for delivering oil through the chamber to the ram passage during reciprocation of the ram.

11. In a machine of the class described, a frame, a ram reciprocable thereon, mechanism for reciprocating the ram, communicating ducts leading from the ram through the reciprocating mechanism, a chamber on the ram parallel therewith communicating

with said ducts, a reservoir on the frame, and a delivery tube leading from the reservoir having a sealing telescopic engagement with the chamber to form therewith a continuous delivery passage to the ducts.

12. In a device of the class described, a frame, a ram reciprocable thereon, a pitman pivoted at its lower end in said frame, a shackle block on said ram, a link pivoted at relatively opposite ends respectively to said block and the upper end of said pitman, passages leading from the upper side of the block through the block across the link to said pitman, a tubular member upon the ram communicating with said passage and closed at one end, and a second tube sealingly telescopically engaged within said tubular member, of substantially less diameter than the member and opening into the member and a reservoir connected with the opposite end of said tube, the connection being at a point above said ram.

13. A reservoir having a vertical intake passage opening at a level therein above the bottom, a vertical overflow passage opening at a level above the vertical intake passage, a drain passage leading from the bottom of the reservoir in the said overflow passage, a delivery passage opening at a level above the other passages having an enlarged upper bore portion and a lower smaller bore portion, a shoulder being formed at the intersection of the bore portions, a wick inserted in the last mentioned passage having a terminal knot of less diameter than the passage and engaged against the shoulder at a point below the level of the bottom of the reservoir, said wick also extending into said reservoir to a point above its bottom, and means attached to the wick and extending through the passage for holding the same in position.

14. A reservoir having vertical intake and overflow passages opening at a level above the bottom of the reservoir, a drain passage leading from the bottom of the reservoir into said overflow passage, a delivery passage at a level above the other passages, and a wick therein having one end extending to a point below the level of the bottom of the reser-

voir and the other extending into the reservoir at a point above its bottom.

15. A reservoir having a vertical intake passage opening at a level therein above the bottom, a vertical overflow passage opening at a level above the vertical intake passage, a drain passage leading from the bottom of the reservoir in the said overflow passage, a delivery passage opening at a level above the other passages having an enlarged upper bore portion and a lower smaller bore portion, a shoulder being formed at the intersection of the bore portions, a wick inserted in the last mentioned passage having a knot therein of less diameter than the passage and engaged against the shoulder, said wick also extending into said reservoir to a point above its bottom, and means attached to the wick and extending through the passage for holding the same in position.

16. A reservoir having a vertical intake passage, opening at a level above the bottom thereof, a vertical overflow passage opening at a level above the said intake passage, a drain passage leading from the bottom of the reservoir into said overflow passage, a delivery passage opening at a level above the other passages and a siphon-like wick extending into the last named passage and into the reservoir with the end in the passage below the level of the end of the reservoir.

17. A lubricating system for machine tools, a frame, a reciprocating ram slidably mounted in said frame, a pitman for reciprocating said ram, a link horizontally disposed connecting said ram and pitman, crank gearing for operating said pitman, an extensible conduit, connected to said frame and ram and communicating with a passage in the ram leading to pivotal connection of the link with said ram, for feeding a liquid lubricant to said pivot, said link being provided with a channel for conveying the liquid lubricant past the connection of the link with the ram to the connection with the pitman and distributing the lubricant to the pitman connections below said link.

In witness whereof, I hereunto subscribe my name.

ROBERT T. HAZELTON.
